HERBERT RÜHLEMANN, OF SOMMERDA, GERMANY, ASSIGNOR TO RHEINISCHE METALLWAAREN- UND MASCHINENFABRIK, OF DUSSELDORF- DERENDORF, GERMANY,
A CORPORATION OF GERMANY

ELECTRIC PERCUSSION FUSE FOR SHELLS, ETC.

Application filed December 16, 1929, Serial No. 414,497, and in Germany June 13, 1929.

The invention relates to electric percussion igniters or fuses for shells or the like which can operate with or without delay, and which receive their ignition energy from a remote point. In accordance with the invention the electric device of the igniter is so constructed that it is possible selectively to set for "delayed ignition" or "ignition without delay" by the special way of supplying the electrical ignition energy. Thereby the charging device for the fuse becomes at the same time the means for setting it to the desired type of ignition. The provision of energy and the setting to "with" or "without" delay follow 10 mutually through a single switching movement of one and the same switch member of the charging device, which can always be arranged in convenient reach of the operator, completely independently of the place and 15 position, at the same, of the current supplying means of the charging device and the fuse itself, either when the latter is in a bomb suspended in readiness for throwing in a throwing device or in a shell already placed in the 20 barrel of the gun.

In the drawing, Figs. 1 and 2 are diagrammatic views of two different forms of the igniter according to the present invention.

In the form of Fig. 1, the percussion fuse A is provided with two complete igniters A' and A², independent of each other and each of which contains a pair of condensers e' and f' or e² and f², connected in opposition to each other through an igniting material h' or h² 35 and a percussion contact g' or g². One of the condensers e' or e² of the igniters A' or A² is closed on itself for unequal potential variation of its energy supply relatively to the other condenser, f' or f², through a high 40 resistance, i' or i². The ignition material h' of igniter A' operates without retardation, while that, h², of igniter A², operates with retardation.

To supply the energy and, at the same time, 45 to make the desired adjustment of the ignition, there is a charging apparatus B, comprising a source of current with three terminals s', s² and s³ for the igniter. To the positive terminal of the source of current can be 50 consecutively connected, by switch s, for ex-

ample, the charging contacts s', s², while the contact s³ is connected to the negative pole. The igniter has four surface contacts k', k², k³ and k⁴, insulated from each other and connected to the corresponding (positive) poles 55 of the condensers e' f', e² and f², and which, when the igniter is in the charging position, engage with the contacts s' and s², in pairs, contacts k' and k² of igniter A, engaging with contact s', and contacts k³ and k⁴ of igniter 60 A² with s². The negative poles of the condensers come in contact with the negative pole s³ of the source of current through the metal of the shell, as shown.

According as to whether retarded or non-retarded ignition is desired, the charging contact s², or the charging contact s', is connected to the positive pole of the source of current by means of the switch s, so that either igniter A' or A² receives the current. Of course, switch s can also be so arranged that the "delay" igniter A² will also receive current, as a precaution, when the "no delay" igniter A' does. The method of operation of the igniters themselves is well known and 75 need not be described here. After the igniter is removed from the charging apparatus, and after a definite period of time, to ensure safety, there exists a potential difference between the condenser coatings, connected to each 80 other through the ignition material, of the igniter which is charged, which produces the ignition when the corresponding percussion contacts are closed.

In the modified form of Fig. 2, the source 85 of current in charging apparatus B is arranged to supply two different potentials, for example, 150 and 200 volts, which can be selectively set up, by means of switch s, between the negative charging contact s³ and the positive pole s'.

Both circuits A' (without delay) and A² (with delay) of the igniter A are maintained, by the charging connections of their condensers, so connected together that, after the insertion of the igniter in the charging apparatus, both are connected to the energized charging contacts s' and s². But in the circuit A', for ignition without delay, there is 95 an electric relay, for example a spark gap 100 l

(gaseous potential arrester), the break-down voltage of which, depending upon its size, lies between the two voltages derived from the source of current.

5 For ignition with delay, the lower potential of the source is supplied to the charging contacts s' and s^3 , by the switch s . At this time only the circuit A^2 receives current, since the relay t prevents the current from entering the circuit A^2 for "no delay" since the momentary charging voltage lies below the voltage necessary to break down said relay. It is only when the higher voltage of the source is imposed at the contacts s' and s^3 , that the "no delay" circuit A' is also charged, and the latter, when percussion takes place, causes an immediate ignition.

I claim as my invention:—

1. Percussion fuse comprising two ignition circuits, either of which can be connected to an outside source of energy, one of said circuits causing undelayed ignition and the other delayed ignition.

2. Percussion fuse comprising two ignition circuits, both of which can be connected to an outside source of energy, one of said circuits operating without retardation and containing a relay, whereby it is capable of being charged only by a voltage of a certain magnitude.

3. Percussion fuse comprising two ignition circuits, each containing a condenser and one containing a relay operable only by a voltage of predetermined magnitude, an outside source of current having two different voltages, and means to connect said circuits to said source.

In testimony whereof I affix my signature.

HERBERT RÜHLEMANN.
